CLAIM

The ornamental design for a lockdown actuator, as shown and described.

DESCRIPTION

FIG. 1 is a front perspective view showing our new design.

FIG. 2 is a front plan view of the new design of FIG. 1.

FIG. 3 is a rear plan view of the new design of FIG. 1.

FIG. 4 is a plan view of the left side of the new design of FIG. 1.

FIG. 5 is a plan view of the right side of the new design of FIG. 1.

FIG. 6 is a plan view of the top of the new design of FIG. 1; and,

(Continued)

FIG. 7 is a plan view of the bottom of the new design of FIG. 1.

1 Claim, 5 Drawing Sheets
